W. G. FISHER

SHUTTLE TRAP OR GUARD FOR LOOMS

Filed Sept. 29, 1922

UNITED STATES PATENT OFFICE.

WILLIAM G. FISHER, OF SUNBURY, PENNSYLVANIA.

SHUTTLE TRAP OR GUARD FOR LOOMS.

Application filed September 29, 1922. Serial No. 591,277.

To all whom it may concern:

Be it known that I, WILLIAM G. FISHER, a citizen of the United States, residing at Sunbury, in the county of Northumberland and State of Pennsylvania, have invented 5 certain new and useful Improvements in Shuttle Traps or Guards for Looms, of which the following is a specification.

This invention relates to looms of all 10 types and has for its object the improvement in shuttle traps or guards for the same, being adapted in the event of a shuttle flying out of the warp to confine the shuttle in the trap or guard and deflect it to the shuttle pocket on 15 either side of the loom and thus safeguard the operator or bystander. It is an improvement on my patent dated Feb. 14, 1922, No. 1,406,835.

In the accompanying drawing, 20 Fig. 1 is a front elevation of the hand rail and lay beam of a loom, with the shuttle guard of my invention attached to the hand rail;

Fig. 2 is an end elevation of the same, 25 looking from right to left in Fig. 1, and showing also the harness, the guard being shown in working position in full lines and in open position in dotted lines;

Fig. 3 is a section on the line 3—3 of 30 Fig. 1, parts being shown in one position in full lines, and in another position in dotted lines; and,

Fig. 4 is a section on the line 4—4 of Fig. 2.

35 Referring to the drawing, 1 indicates the hand rail, 2 the lay beam, and 9 the harness of a loom. Metal hinge-pieces 3 are secured to the top of the lay beam, and a shuttle guard, indicated as a whole by the reference 40 character *g*, is connected to the hinge-pieces so that it may swing from the normal position of the guard, shown in full lines in Fig. 2, to the dotted line position shown in said figure, wherein arms 8 on the ends of 45 the guard engage the harness. The guard comprises metal end plates 7, a plurality of curved retaining arms 6, which are spaced apart from one another, and a plurality of rods 5 which extend longitudinally of the 50 lay beam and hand rail between the end plates 7 and through suitable openings in the retaining arms. The end plates and the retaining arms are hinged to the hand rail by a hinge-rod 4, which extends 55 through said parts and into the hinge-piece 3. The retaining arms extend

outwardly from the hand rail over the lay beam and thence downwardly to points adjacent the latter, and the rods which are carried by the arms and end plates are 60 spaced apart in a curved series overlying the lay beam. Plates 7^a, integral with or secured to the end plates 7, extend downwardly and outwardly from said plates and form deflectors for deflecting the shuttle 65 s downwardly, if it flies off of the lay beam in its passage along the latter.

It will be understood that if the shuttle leaves its course, it will strike the longitudinal rods which will prevent it from flying 70 upwardly, and at the end of the guard it will strike a deflector plate and be directed into a pocket (not shown) at the end of the beam.

When the loom is stopped and it is desired 75 to raise the shuttle guard so that the operator may have access to the threads, the guard is thrown upwardly, as shown in dotted lines in Fig. 2, and the rods 8 on the guard rest against the harness. If the loom 80 should now be started with the guard in the position indicated, the movement of the harness will tip the guard and it will drop forward into its full line position shown in Fig. 2. Thus, it is impossible to operate 85 the loom with the guard out of its operative position. When the guard drops into its operative position, the catch 10 on the lay beam enters a notch 10^a in one of the end plates 7 and locks the guard in its lowered 90 position.

What I claim is:

1. In a shuttle guard for looms, end plates having downwardly and outwardly extending portions, forming deflectors, and a plurality of bars extending between said end plates and spaced apart in a curved series adapted to overlie the lay beam of a loom. 95

2. In a shuttle guard for looms, an open-work frame comprising end plates having 100 downwardly and outwardly extending portions, forming deflectors, a series of curved retaining members between said end plates, and a series of spaced bars extending between the end plates and connected to said 105 bars.

3. The combination with the hand rail and lay beam of a loom, of a shuttle guard comprising end plates hinged to the hand rail and having downwardly and outwardly extending parts, forming deflectors, curved retaining arms extending from the hand rail 110

over the lay beam and thence downwardly toward said beam, and a plurality of rods spaced apart from one another and extending between the end plates, said rods being connected to said arms.

5. The combination with the hand rail, lay beam and harness of a loom, of a shuttle guard hinged to the hand rail and adapted to normally extend over the lay beam, said

guard having a part adapted to engage the harness when the guard is swung upwardly over the hand rail, whereby the operation of the harness will return the guard to normal position.

In testimony whereof I affix my signature.

WILLIAM G. FISHER.
